SLUDGE TANK HAVING A U-SHAPED CONDUIT HAVING ARM PORTIONS INCLINED DOWNWARD TO THE LOWER PART OF SAID TANK AND A CONDUIT OPENING INTO SAID TANK CONNECTING SAID PORTIONS

Henry W. Hapman, Detroit, Mich.

Application January 15, 1944, Serial No. 518,454

14 Claims. (Cl. 210—55)

1

The present invention relates to self-cleaning coolant tanks, and more particularly, to an apparatus for collecting sludge and the like from said tank.

The primary object of the invention is to provide a self-cleaning coolant tank in the system of a grinding machine or the like employing a coolant for reducing the temperature of the work while being ground and to provide a device which is portable and may be readily moved from one location to another adjacent the grinding machine.

Another object of the invention is to provide a coolant tank of the above-mentioned type having a sludge conveying and collecting system for continuously moving the sludge and other foreign matter in the coolant liquid so that the coolant liquid may be recirculated to the grinding machine.

Another object of the invention is to provide a self-cleaning coolant tank of the above-mentioned character which may be operated continuously or during intervals so as to maintain the coolant liquid in a clean condition and to prevent the collection of large quantities of sediment in the bottom of the tank to contaminate the coolant liquid.

Another object of the invention is to provide a self-cleaning coolant tank which is entirely automatic and requires very little attention on the part of the grinding machine operator so as to maintain the coolant liquid free of sediment and sludge collected during the grinding operation.

Another object of the invention is to provide an inlet for the coolant liquid as it is discharged from the grinding machine directly above a compartment formed by a baffle plate so that foam and the like may be removed from the surface of the liquid through an opening at one side of the coolant tank directly opposite the inlet.

Another object of the invention is to provide a self-cleaning coolant tank of the above-mentioned character having a uniquely constructed sediment and sludge collector of the endless conveyor type which is adapted to travel a circuitous path and traverse the bottom of the self-cleaning coolant tank during a portion of said circuitous path.

Other objects and advantages of the invention

2

will become apparent during the course of the following description of the accompanying drawings, wherein:

Figure 1 is a side elevational view of the coolant tank embodying the invention, illustrating the same in position adjacent the centerless grinding machine, and illustrating the manner in which the conveyor is arranged to collect sludge and sediment from the tank and convey the same to a point of discharge;

Figure 2 is a top plan view of the coolant tank showing the conveyor disconnected therefrom to illustrate the general shape and design of the casing structure;

Figure 3 is a top plan view of the conveyor tubing illustrating the general shape thereof and showing the reduced intermediate section for being welded to the sloping walls of the coolant tank so that the free ends may project upwardly to a point of discharge;

Figure 4 is an enlarged cross-sectional view illustrating the manner in which the sloping walls of the coolant tank are welded to the intermediate portion of the conveyor tube;

Figure 5 is a vertical cross-sectional view showing the discharge end of the conveyor tubes greatly enlarged, illustrating the manner in which the sludge and sediment is removed by the endless conveyor;

Figure 6 is a plan view showing in detail one of the conveyor flights for the conveyor illustrating the manner in which the same is cut out to accommodate the conveyor chain;

Figure 7 is a transverse cross-sectional view through the conveyor chain illustrating the manner in which the conveyor flights are bolted thereto by oppositely extending lugs on opposite sides of the conveyor chain;

Figure 8 is a cross-sectional view on line 8—8 in Figure 1 showing the manner in which the free ends of the conveyor tube are welded to an interconnecting plate which is welded or otherwise fastened in place;

Figure 9 is a top view greatly enlarged showing the manner in which the motor support and conveyor sprocket are adjustably supported adjacent the free end of the conveyor tube;

Figure 10 is a longitudinal sectional view on line 10—10 in Figure 9 looking in the direction of the arrows, illustrating in detail the manner in

which the adjustable motor and sprocket supporting plates are carried by the free ends of the conveyor tubes; and

Figure 11 is an end elevational view of the adjustable motor supporting base showing the manner in which the sprocket is supported for being driven by the motor on the underside of said plate.

Brief description of the invention

The invention broadly comprises a tank having sloping bottom walls and baffle partitions for the reception of a coolant fluid circulated over the grinding wheels of a centerless grinder so as to cool the work during grinding. The coolant with the particles of metal or the like is then returned to the tank and the sludge therein and other sediment is collected in the bottom of the tank where it is adapted to be removed by an endless conveyor arranged and positioned so as to convey the sludge and sediment to a point of discharge remote from the tank. In grinding machines of the centerless type, the coolant tank associated with the circulatory system becomes filled with sediment and sludge to such an extent as to stop circulation of the coolant liquid and create obnoxious odors, and it is frequently necessary to remove the sludge and sediment by manual labor which requires the centerless grinding machine to be thrown out of operation until the removal of the sediment and sludge has been completed.

The above objections and disadvantages are overcome by providing a uniquely constructed tank which may be presented to the discharge of the centerless grinder so as to collect the coolant with the abrasive and other particles so that the particles will be collected at the bottom of the tank and discharged over a suitable receptacle which may be easily emptied when full and thereby prevent the centerless grinder from being out of operation over long periods of time and at the same time maintain the coolant liquid in clear, clean condition. Another advantage inherent in the coolant tank embodying this invention resides in the fact that foam and the like may be removed from the tank from the liquid level thereof adjacent the inlet opening of the tank so that said foam will not overflow and cause objectionable odors and appearance.

Detailed description of the invention

In the drawings, Figure 1 shows a preferred form of the invention comprising a collection and sediment tank 5 of rectangular construction having a pair of side walls 6 connected at one end by an end wall 7 and at the other end by an end wall 8. Connecting the side walls 6 and welded or otherwise secured to the sloping edge 9 thereof is a sloping bottom wall 11 (Figure 4) having a depending flange portion 12 and the extreme lower portion of the sloping bottom wall 11 is tapered inwardly at both ends as at 13. A sloping bottom wall 14 extends from the end wall 8 to a point adjacent the lower end of the sloping wall 11 and said end wall is also provided with a depending flange 15 similar to the flange 12 and arranged in parallel relation thereto. The sloping wall 14 is slightly reduced in width as shown in Figure 2 in dotted lines and is spaced from the side walls 6 and the tapered portion 13 of the sloping wall 11 as well as the reduced sloping wall 14. A plate 17 is welded in place to the side wall 6 adjacent each end or side of the reduced sloping bottom wall 14. Said

plates may be welded along the edges to the reduced sloping wall 14 and may have extensions adjacent the lower portions provided with arcuately cut out areas to facilitate the passage of the conveyor structure which will be hereinafter more fully described.

A cover plate 19 is welded or otherwise secured to the top edge of the side walls 6 and end walls 7 and 8 and said cover 19 terminates at one of its ends a short distance from one of the walls 7 so as to provide a space therebetween, a portion of which is adapted to be closed by a hinged closure 20 hinged to the top wall 19 as at 21. The remaining portion of the opening is closed by a frame 23 having sloping walls 24 to form a framework for a screened inlet 25. One end of the casing has its side wall 6 cut away as at 26 at a point near the liquid level of the coolant tank so that foam collecting on the top of the liquid may be withdrawn or removed by scooping the same toward one end of the casing. The closure 20 is adapted to facilitate the replenishing of the coolant liquid and the addition of various ingredients thereto from time to time. Extending between the side walls 6 and terminating adjacent the sloping bottom wall 11 is a partition 28 which extends downwardly from the edge of the top wall 19 so as to form a compartment adjacent the entrance or coolant liquid inlet so that the heavier particles will be directed downwardly toward the sloping bottom wall 11 when the coolant liquid is circulated through the tank. Similarly, a partition wall 29 extends between the reduced sloping floor 14 and terminates a short distance from the top wall 19 and said partition interconnects the plates 17 and the end wall 8 so as to form a chamber for the sludge and sediment in the tank. The coolant liquid passing through the tank is adapted to overflow the baffle 29 at the top thereof as at 30 so as to fill a compartment having tapering walls 31 and an end wall 32. The end wall 8 forms the other wall of the liquid coolant chamber and completes the structure with the bottom wall 33 extending between the end walls 8 and 32. The top of the liquid coolant chamber on the left side of the tank is closed by a cover plate 34, and mounted on said cover plate is a circulatory pump apparatus 35 including a motor and suitable gearing with the motor shaft extending downwardly through a tube 36 to a point adjacent the floor 33 where it is connected to the rotor of a sump pump 37. The outlet side 38 of the sump pump is connected by a tube or conduit 39 to a supply pipe 40 the end of which is connected to the centerless grinder for supplying the coolant liquid to the wheels thereof. The sump pump 37 may be of the centrifugal type and is provided with a centrally positioned inlet in communication with the coolant liquid chamber to the left of the coolant tank.

Secured to the depending flanges 12 and 15 of the respective sloping bottom walls 11 and 14 is a short length of pipe 41 (Figure 4) diametrically divided and cut away a distance equal to the space between the edges of the sloping wall 14. The depending flanges 12 and 15 are welded as at 42 to the edge of the divided pipe to form a trough 43 of semi-circular shape. The ends of the semi-circular trough 43 are welded to the plates 17 adjacent the openings therein so as to aid in spacing said plates. Elbow sections 45 are welded or otherwise secured to the outer sides of the plates 17 and the ends of the semi-circular trough portion 43, and said elbow fittings 45 are

provided with relatively straight portions 46 terminating in angularly disposed discharge and inlet ends 47 and 48 respectively. The extreme free ends of the pipes 47 and 48 are flared outwardly as at 49 and 50 to allow the free passage of the endless conveyor adapted to travel through the tubes 47 and 48 and also traverse the semi-circular trough 43. As shown in Figure 1, the relatively straight portions 46, 47 and 48 of the conveyor tubes are angled with respect to the horizontal and are inclined upwardly from the semi-circular trough 43 to a point of termination adjacent the top 5. It is to be noted that the free end portions 47 and 48 extend along the side walls 31 of the coolant chamber and an angle bracket 52 is welded to the end wall 32 of the coolant chamber for supporting the tubes 47 and 48 at each end thereof.

Mounted between the free projecting ends of the tubes 47 and 48 is a supporting plate 53 having obliquely cut edges 54 which are adapted to be welded as at 55 (Figure 8) along the top of the conveyor tubes 47 and 48. The plate 53 is adapted to hold the free ends of the conveyor tubes together and to form a support for a motor sprocket drive including a pair of spaced parallel bars 56 (Figure 9) bolted or otherwise fastened to the plate 53 as at 57. The bars 56 project beyond the plate 53 and bolted to the bars 56 is a pair of similar bars 58 spaced by means of spacer strips 59. Bolts 60 are passed through the strips 56, 58 and 59 and it is noted that the space between the strips 56 and 58 forms a guideway for receiving a sliding plate 61 having a lug at one end thereof as at 62 to which is pivotally attached a screw-threaded shaft 63 by means of a pivot pin or the like as at 64. The screw shaft 63 is received in an aperture formed in a lug 65 connected with the plate 53 and suitable nuts 66 are mounted on the rod 63 in threaded relation therewith, and on opposite sides of the lug 65 to permit adjustment of the sliding plate 61 along the ways provided by the spaced parallel bars 56 and 58.

Secured to the sliding plate 61 is an electric motor 68 having a reduction gear casing 69 in the lower portion thereof and the shaft of said reduction gearing is adapted to project through an opening 70 in the plate 61 so as to be drivingly connected to a sprocket wheel 71 suitably keyed thereto as by means of a gib and slot connection. A spacer sleeve 72 is mounted on the shaft between a washer 73 on the underside of the plate 61 and the sprocket 71 so as to space the sprocket a sufficient distance from the plate 61 and permit the conveyor structure to pass under. A switch 74 is provided on the motor 68 and said switch may be connected with a domestic source of current to supply the motor 68.

Extending through the conveyor tubes 47 and 48 in the relatively straight sections 46 and 60 trained over the sprocket 71 is a conveyor chain generally designated by the reference character 75 comprising links 76 having alternate pivot pins 77 and pivot pin socket members 78. Each chain link 76 is provided with a pair of oppositely extending wing-like lug members 79 projecting from opposite sides of said links in a lateral direction and the free ends of said lugs are apertured for the passage of bolts 80 which bolts are adapted to pass through the openings 81 in the conveyor 70 flight members 82 (Figure 6). Nuts 83 may be threaded on the bolts 80 to retain the disc-shaped flights 82 in place and said flights are backed by a disc-like plate 84 to add a certain amount of rigidity thereto. The flight elements 82 may be 75

formed of resilient material or composition which lends itself readily to the particular construction and the use desired. Each backing plate 84 and conveyor flight 82 is slotted respectively as at 85 and 87 to permit the same to traverse the sprocket wheel 71 as the flights pass therearound. It is to be noted that the conveyor flights 82 and backing plates 84 while being of different diameters are shaped and formed so as to traverse the trough 43 and remove the sediment or sludge therefrom deposited from the tank 5.

The discharge conduit 47 is provided with a shield plate 88 welded or otherwise fastened in place as shown in Figure 5 and said shield plate is 15 adapted to catch drippings from the flared end 49 and prevent the same from flowing downwardly along the outside of the conveyor tube 47.

The side walls 6 of the tank 5 are provided with vertical leg members 89 while the end wall 32 20 of the coolant chamber is provided with an adjustable leg 90 having a foot portion 91 to facilitate the supporting of the tank adjacent a centerless grinder generally indicated by the reference character G. The leg 90 is adjustably held in place by means of bolts or the like as at 92.

A relatively large receptacle 93 may be positioned under the sprocket wheel 71, discharge end 30 of the conveyor tube 47 and directly below the depending lip 88 so as to catch the discharge from the tank 5 when the motor 68 is in operation, and facilitate the removal of the sludge and sediment therein from a point remote from the tank.

The grinder G is typical of a conventional centerless grinder and embodies a base B having spindle supports C for rotatably mounting a pair of grinding wheels D. The frame B is provided with an extension trough E directly beneath the grinding wheels D so as to catch and collect the coolant liquid after the same has passed over the material being ground between the grinding wheels D. A discharge opening or spout F is formed in the trough E and said discharge spout F is adapted to be positioned directly above the screened inlet 25 so that the coolant liquid will pass from the trough E directly into the tank 5. After the coolant liquid passes into the tank through the screened opening 25 it is caused to travel downwardly adjacent the sloping floor 11 and under the baffle 28 so that the heavier particles will be 50 guided downwardly toward the semi-circular trough 43. The coolant liquid will then pass over the top edge 30 of the baffle wall 29 where it will enter the coolant chamber so as to be recirculated back to the grinder G by means of the centrifugal sump pump 37 through the tube 40. The tube 40, generally a part of the grinder, is coupled with the upper end of the discharge tube 39 and upon operation of the motor 35 circulation of the liquid will be effected. As the sludge or sediment collects in the semi-circular trough 43 in the lower part of the sloping walls 11 and 14 it may be desired to remove the sludge so as to be collected in a receptacle 93. In order to remove the sludge, the motor 68 is started by manipulating the switch 74 so as to cause the conveyor chain to traverse the sprocket wheel 71 and pass through the conveyor tubes 47 and 48 so as to withdraw the sludge and sediment to the outer flared end 49.

In addition to permitting the conveyor flight to pass around the sprocket wheel, the slots 86 allow the coolant liquid to return from successive flights as they reach the flared opening 49 and thereby prevent pumping of the coolant liquid and removal of the sludge S.

If desired, the pipe section 41 may be slightly

smaller in diameter than the conduit sections 46, 47 and 48 so that as the conveyor flights traverse the semi-circular trough 43, a relatively tight fit therebetween will be had while conveyor flights travelling through the conveyor tubes 46, 47 and 48 will be permitted a greater clearance so that the coolant liquid may run back from one flight to the other and prevent the same from being pumped out of the discharge tube 47. It is also to be noted that the flared end 49 of the discharge tube 47 relieves the flights of any pumping action as they near the flared end by the greatly increased diameter of the discharge pipe so as to further eliminate pumping of the coolant liquid as it travels toward said discharge.

When the conveyor 75, including the chain structure 16 and the flight elements 82, has become worn on one of their diametrical sides, the conveyor 75 may be removed and reversed so as to bring the other diametrical side in contactual wiping engagement with the tubes 84 and the tubes 47 and 48 and trough 43. Since it is necessary to mount the conveyor in the position reversed to its position shown in the drawing during such a change, it is obvious that the motor 68 would have to be reversed so as to change the direction of conveyor travel. In this event the discharge tube 48 would become the outlet and the tube 47 the inlet.

It is to be understood that the form of the invention herewith shown and described is to be taken as a preferred embodiment of the same and that various changes may be made in the shape, size and arrangement of parts without departing from the spirit of the invention or the scope of the subjoined claims.

What I claim is:

1. A sludge removal apparatus comprising a receptacle having a downwardly-sloping bottom wall, an approximately U-shaped conduit structure having tubular arm portions inclined downward to the lower part of said receptacle and a connecting conduit portion extending through the lower part of said receptacle and interconnecting said arm portions, said connecting portion having an opening in the upper part thereof for the passage of the sludge settling downward in the receptacle, an endless conveyor mounted in said conduit structure and having a portion extending externally thereof, and power-actuated driving mechanism drivingly engaging the external portion of said flight conveyor for moving said conveyor through said conduit structure.

2. A sludge removal apparatus comprising a receptacle having a downwardly-sloping bottom wall, an approximately U-shaped conduit structure having tubular arm portions inclined downward to the lower part of said receptacle and a connecting conduit portion extending through the lower part of said receptacle and interconnecting said arm portions, said connecting portion having an opening in the upper part thereof for the passage of the sludge settling downward in the receptacle, an endless conveyor mounted in said conduit structure and having a portion extending externally thereof, and power-actuated driving mechanism drivingly engaging the external portion of said flight conveyor for moving said conveyor through said conduit structure, said driving mechanism including a driving wheel mounted between and adjacent the outer ends of said arm portions of said conduit structure and drivingly engaging said conveyor.

3. A sludge removal apparatus comprising a receptacle having a downwardly-sloping bottom

wall, an approximately U-shaped conduit structure having tubular arm portions inclined downward to the lower part of said receptacle and a connecting conduit portion extending through the lower part of said receptacle and interconnecting said arm portions, said connecting portion having an opening in the upper part thereof for the passage of the sludge settling downward in the receptacle, an endless conveyor mounted in said conduit structure and having a portion extending externally thereof, and power-actuated driving mechanism drivingly engaging the external portion of said flight conveyor for moving said conveyor through said conduit structure, said driving mechanism including a driving wheel mounted between and adjacent the outer ends of said arm portions of said conduit structure and drivingly engaging said conveyor, the lower portions of said flight conveyor being guided solely by said conduit structure whereby to obviate guide wheels in said receptacle.

4. A sludge removal apparatus comprising a receptacle having a downwardly-sloping bottom wall, an approximately U-shaped conduit structure having tubular arm portions inclined downward to the lower part of said receptacle and a connecting conduit portion extending through the lower part of said receptacle and interconnecting said arm portions, said connecting portion having an opening in the upper part thereof for the passage of the sludge settling downward in the receptacle, an endless conveyor mounted in said conduit structure and having a portion extending externally thereof, and power-actuated driving mechanism drivingly engaging the external portion of said flight conveyor for moving said conveyor through said conduit structure, said conduit structure having bends therein adjacent the junctions of said arm portions with said connecting portion and said flight conveyor directly engaging the inner walls of said bends for guidance and alteration of direction of travel.

5. A sludge removal apparatus comprising a receptacle having a downwardly-sloping bottom wall, an approximately U-shaped conduit structure having tubular arm portions inclined downward to the lower part of said receptacle and a connecting conduit portion extending through the lower part of said receptacle and interconnecting said arm portions, said connecting portion having an opening in the upper part thereof for the passage of the sludge settling downward in the receptacle, an endless conveyor mounted in said conduit structure and having a portion extending externally thereof, and power-actuated driving mechanism drivingly engaging the external portion of said flight conveyor for moving said conveyor through said conduit structure, the lower part of said receptacle having openings in its opposite ends aligned with said connecting portion and said conduit arm portions extending downward outside said receptacle and communicating with said connecting portion through said openings.

6. A sludge removal apparatus for reconditioning and recirculating coolant liquid for machine tools, comprising a receptacle having side and end walls connected by downwardly sloping bottom walls and having an inlet for sludge-contaminated coolant liquid, said bottom walls converging at their lower ends and terminating in an open-topped trough open at each end, tubular conveyor tubes connected to the trough and extending obliquely upward to the upper portion of said receptacle, a support mounted at the free

ends of said conveyor tubes, a sprocket journaled on said support, a motor carried by said support and drivingly connected to said sprocket, an endless conveyor connected to said sprocket and passing through said conveyor tubes into said trough, and a pump in communication with said receptacle at a location remote from said coolant liquid inlet and the trough for circulating said liquid to the machine tool.

7. A sludge removal apparatus for reconditioning and recirculating coolant liquid for machine tools, comprising a receptacle having side and end walls connected by downwardly sloping bottom walls and having an inlet for sludge-contaminated coolant liquid, said bottom walls converging at their lower ends and terminating in an open-topped trough open at each end, tubular conveyor tubes connected to the trough and extending obliquely upward to the upper portion of said receptacle, a support mounted at the free ends of said conveyor tubes, a sprocket journaled on said support, a motor carried by said support and drivingly connected to said sprocket, an endless conveyor connected to said sprocket and passing through said conveyor tubes into said trough, and a pump in communication with said receptacle at a location remote from said coolant liquid inlet and the trough for circulating said liquid to the machine tool, said conveyor having spaced apart flight members adapted to remove sediment from said trough and convey the same to a point remote from the receptacle.

8. A sludge removal apparatus for reconditioning and recirculating coolant liquid for machine tools, comprising a receptacle having side and end walls connected by downwardly sloping bottom walls and having an inlet for sludge-contaminated coolant liquid, said bottom walls converging at their lower ends and terminating in an open-topped trough open at each end, tubular conveyor tubes connected to the trough and extending obliquely upward to the upper portion of said receptacle, a support mounted at the free ends of said conveyor tubes, a sprocket journaled on said support, a motor carried by said support and drivingly connected to said sprocket, an endless conveyor connected to said sprocket and passing through said conveyor tubes into said trough, and a pump in communication with said receptacle at a location remote from said coolant liquid inlet and the trough for circulating said liquid to the machine tool, said conveyor including an endless chain having disc-shaped conveyor flights secured thereto adapted to remove sediment from said trough and convey the same to a point exterior of said receptacle.

9. A sludge removal apparatus for reconditioning and recirculating coolant liquid for machine tools, comprising a receptacle having side and end walls connected by downwardly sloping bottom walls and having an inlet for sludge-contaminated coolant liquid, said bottom walls converging at their lower ends and terminating in an open-topped trough open at each end, tubular conveyor tubes connected to the trough and extending obliquely upward to the upper portion of said receptacle, a support mounted at the free ends of said conveyor tubes, a sprocket journaled on said support, a motor carried by said support and drivingly connected to said sprocket, an endless conveyor connected to said sprocket and passing through said conveyor tubes into said trough, and a pump in communication with said receptacle at a location remote from said coolant liquid inlet and the trough for circulating said liquid to the machine tool, said inlet having a screened entrance portion adapted to receive coolant liquid from said machine tool and direct the

said liquid to the machine tool, said conveyor comprising an endless flexible member having a series of disc-shaped conveyor flights attached to said endless member in spaced apart relation adapted to remove sediment from said trough and convey the same to a point of discharge remote from said receptacle.

10. A sludge removal apparatus for reconditioning and recirculating coolant liquid for machine tools, comprising a receptacle having side and end walls connected by downwardly sloping bottom walls and having an inlet for sludge-contaminated coolant liquid, said bottom walls converging at their lower ends and terminating in an open-topped trough open at each end, tubular conveyor tubes connected to the trough and extending obliquely upward to the upper portion of said receptacle, a support mounted at the free ends of said conveyor tubes, a sprocket journaled on said support, a motor carried by said support and drivingly connected to said sprocket, an endless conveyor connected to said sprocket and passing through said conveyor tubes into said trough, and a pump in communication with said receptacle at a location remote from said coolant liquid inlet and the trough for circulating said liquid to the machine tool, at least one of said conveyor tubes having its free end flared outwardly to prevent pumping of the liquid by said conveyor.

11. A sludge removal apparatus for reconditioning and recirculating coolant liquid for machine tools, comprising a receptacle having side and end walls connected by downwardly sloping bottom walls and having an inlet for sludge-contaminated coolant liquid, said bottom walls converging at their lower ends and terminating in an open-topped trough open at each end, tubular conveyor tubes connected to the trough and extending obliquely upward to the upper portion of said receptacle, a support mounted at the free ends of said conveyor tubes, a sprocket journaled on said support, a motor carried by said support and drivingly connected to said sprocket, an endless conveyor connected to said sprocket and passing through said conveyor tubes into said trough, and a pump in communication with said receptacle at a location remote from said coolant liquid inlet and the trough for circulating said liquid to the machine tool, said receptacle having pattern walls to cause liquid fed to said receptacle to follow a sinuous path directly above said trough.

12. A sludge removal apparatus for reconditioning and recirculating coolant liquid for machine tools, comprising a receptacle having side and end walls connected by downwardly sloping bottom walls and having an inlet for sludge-contaminated coolant liquid, said bottom walls converging at their lower ends and terminating in an open-topped trough open at each end, tubular conveyor tubes connected to the trough and extending obliquely upward to the upper portion of said receptacle, a support mounted at the free ends of said conveyor tubes, a sprocket journaled on said support, a motor carried by said support and drivingly connected to said sprocket, an endless conveyor connected to said sprocket and passing through said conveyor tubes into said trough, and a pump in communication with said receptacle at a location remote from said coolant liquid inlet and the trough for circulating said liquid to the machine tool, said inlet having a screened entrance portion adapted to receive coolant liquid from said machine tool and direct the

11

same downwardly into the vicinity of said trough.

13. A sludge removal apparatus for reconditioning and recirculating coolant liquid for machine tools, comprising a receptacle having side and end walls connected by downwardly sloping bottom walls and having an inlet for sludge-contaminated coolant liquid, said bottom walls converging at their lower ends and terminating in an open-topped trough open at each end, tubular conveyor tubes connected to the trough and extending obliquely upward to the upper portion of said receptacle, a support mounted at the free ends of said conveyor tubes, a sprocket journaled on said support, a motor carried by said support and drivingly connected to said sprocket, an endless conveyor connected to said sprocket and passing through said conveyor tubes into said trough, and a pump in communication with said receptacle at a location remote from said coolant liquid inlet and the trough for circulating said liquid to the machine tool, a partition in said receptacle separating said circulating pump from the remainder of said receptacle and a motor drive mechanism on the top of the receptacle above said pump for driving the same.

14. A sludge removal apparatus for reconditioning and recirculating coolant liquid for machine tools, comprising a receptacle having side and end walls connected by downwardly sloping bottom walls and having an inlet for sludge-contaminated coolant liquid, said bottom walls converging at their lower ends and terminating in an open-topped trough open at each end, tubular conveyor tubes connected to the trough and extending obliquely upward to the upper portion of said receptacle, a support mounted at the free ends of said conveyor tubes, a sprocket journaled on said support, a motor carried by said support and drivingly connected to said sprocket, an endless conveyor connected to said sprocket and passing through said conveyor tubes
